UNITED STATES PATENT OFFICE

JOHN HENRY ELVIDGE BAKER, OF ALDWYCH, LONDON, ENGLAND, ASSIGNOR TO INTERNATIONAL STANDARD ELECTRIC CORPORATION, OF NEW YORK, N. Y.

AUTOMATIC TELEPHONE SYSTEM USING SINGLE MOTION SWITCH BY-PATH CIRCUITS

Application filed June 26, 1930, Serial No. 463,920, and in Great Britain July 3, 1929.

This invention relates to automatic or semi-automatic telephone systems and is more particularly concerned with systems using single-motion switches wholly or in part for setting up a connection.

In such systems it has been proposed to use selective stages comprising one or more additional switches individual to each conversational switch or common to a group of such switches for use in setting up a connection.

Such systems are of two main types which may be called the auxiliary control and by-path systems respectively: by auxiliary control is meant a system in which the impulses for setting a selecting stage are received by a switch other than the conversational switch, the latter hunting for a contact marked by the former: in this arrangement further progress in the connection takes place entirely over the conversational switches.

In the by-path systems, a switch other than the conversational switch hunts for and tests the wanted outlet or outlets: the connection is temporarily extended over said switch, and is later transferred to the conversational switch.

In both these systems, the switch over which the connection is immediately extended may have to hunt over the greater portion of the whole of its contact bank, the time taken being too large a proportion of the interdigital space for safety. The object of the present invention is to provide modifications in or combinations of the above systems whereby the time taken in switching through a connection in response to higher digit values, either over the conversational switch or another switch is greatly reduced.

Three arrangements will be described generally and one of these will be further described in detail, but it is to be understood that the invention is not limited to these arrangements but is capable of any modification within the scope of the appended claims.

According to one method by which the desired object may be obtained, digits up to five in value for instance are received entirely by a control switch, the conversational

switch setting up the connection: any impulses beyond the number given above are received by the conversational switch and an immediate connection is set up in the early part of the control switch, the conversational switch then moving on to the required position in its own time. 55

According to another method two switches other than the conversational switch may be used in a manner similar to that described, 60 in the first method, a non-homing conversational switch being marked from the switch used.

One of the features of the invention consists in a switching stage comprising a plurality of switches including a conversational switch in which one of the switches finds the group of outlets indicated by a digit at a position nearer the home position than the position ultimately taken up by the conversational switch in setting up the connection. 70

Another feature of the invention consists in circuit arrangements for a selecting stage in which different parts of the same digit may step different switches. 75

Other features of the invention will be apparent from the description and will be set out in the appended statement of claim.

The first method described above will be more particularly described with reference to the accompanying drawings in which Figs. 1A and 1B which should be arranged with Fig. 1A to the left of Fig. 1B show a group selecting stage comprising a conversational switch and a control or by-path circuit common to a number of such switches. A similar arrangement could, of course, be used at a final selector stage. 85

The levels M, N respectively of the conversational and control switches IR, CR, are used for marking purposes. The level M is divided up into ten groups I—X of any desired size, while level N has five marking contacts 1—5 followed by five groups VI—X corresponding to those in level M. Corresponding contacts in groups VI—X of levels M, N are connected together. If the digit is five or under, the impulses are received on switch CR and the required group in level M is marked from a contact in level N. If the 100

digit is greater than two, switch IR chases to its 20th contact and stops there until the end of the digit, when it again steps to find the marked group and hunt therein. If the digit 5 is greater than five, the additional impulses step switch IR from its 20th contact and switch CR chases and sets up a by-pass connection: IR then finds the selected outlet and the connection is finally switched through. 10 The contact 20 of IR is chosen as a starting point for the reception of impulses as being the farthest point IR can reach with safety to be ready to receive the later impulses. It will be seen that an outlet is always found in 15 the early part of one of the switches.

When the group selecting stage is seized, relays K and 2 in the individual and common circuits respectively operate in a circuit from battery via both windings of 2 in parallel, 20 normal springs CN1, both windings of K, IN1, contact i_1 , test conductor T to earth at the preceding stage. Impulse relay 1 then operates from battery over its lower winding ch_3, k_4, ih_3 , calling loop, ih_4, k_6, ch_4 , upper winding of 1 to earth. Release relay 4 operates to earth at contact 11, and relays 2, K lock up over contacts 21, $k_2, ih_1, k_1, 41$, to earth.

30 Relay 8 operated immediately relay K pulled up from earth via wipers N, M of the auxiliary and conversational switches CR, IR, respectively k_9 and 73.

When the next digit is dialled, relay i is impelled, and switch CR is stepped thereby in 35 a circuit via 51, 42, 93, ch_6 , 11 to earth, the slow to release relay 3 being energized in parallel therewith.

40 Relay 8 will de-energize, when switch CR and a stepping circuit will be closed for switch IR via its interrupter contacts, $k_3, 61, 92, ch_7, 81$ to earth. If the digit is 1 or 2 when switch IR reaches the first contact of the respective group I or II in its contact bank, relay 8 pulls up to stop the switch 45 IR at its contacts 81 and to enable relay 7 to operate when relay 3 falls back at the termination of the impulses. Relay 7 is two-step, and energized first over its upper winding, via 43, 75, 82, to earth and operates its 50 light contact 72, so that when, after relay 3 has fallen back at the end of impulsing, and relay 8 has operated relay 7 pulls up and at its contacts 73 releases releasing relay 8.

55 If the digit was 3, 4 or 5, switch IR would be stopped on contact 20 by the energization of relay 8 from earth on 34. When relay 3 releases at the end of dialling, relay 8 releases and IR again steps on until the first contact of the marked group III, IV, or V is reached. 60 Relay 8 then operates momentarily to energize relay 7 fully. A self stepping circuit is thereby formed for IR via $k_3, 61, 92$ and in parallel, $ch_5, 71, 31$, to earth, and $ch_7, 81$ to earth. Operation of relay 7 in either case 65 closes a test circuit from earth via 74, upper

winding of relay CH, 64, k_8 and the test wiper It of the conversational switch so that when the switch reaches an idle contact in the marked group, relay CH energizes, opening the stepping circuit of IR at ch_5, ch_7 . Relay CH locks $ch_9, ch_1, 41$ and energizes relay IH via $k_7, ch_8, 62$ to earth. The connection is switched through to the positive and negative wipers IA, IB at ih_3, ih_4 . Relays 1, 4 are released, and the circuit of relays K, 2 is opened at ch_1 . The switch CR is homed via interrupter contacts ch_2 , off-normal contacts CN2, 41, to earth.

If the switch IR should find all the wanted group engaged, relay CH does not pull up and relay 9 will energize to earth over contacts $ch_{10}, 73, k_9$, wiper and last terminal in the group and contacts 33, ch_{11} . Relay 9, opening the circuit of IR at 92, connecting up busy tone BT at 91, and opening the impulse stepping circuit of CR at 93.

If the digit is over five, the operations will be as follows: When switch CR reaches contact 5, relay 5 will operate over wiper N and lock up at 52. The impulsing circuit is immediately switched over to switch IR at 51 via k_5 so that the remaining impulses from the sixth upwards step switch IR forward from its 20th contact. While switch IR is on its 21st contact (marked 6), relay 6 operates via 45, jumpered bank contacts of wiper N, M, wiper M, $k_9, 73$, relay 8 to battery. Relay 8 does not operate in this circuit. Relay 6 locks up over both windings in series, closes a self-stepping circuit for CR at 61, prepares a modified circuit for relay IH at 62 and a stepping circuit for IR at 63, and changes over the testing circuit at 64 from wiper It to wiper Ct of the control switch. When the wiper N reaches the marked first contact of one of the groups VI, VII, VIII IX or X relay 8 operates momentarily to energize relay 7 fully and switch CR continues hunting for a free contact in a manner similar to that described before for IR. When the switch finds a free outlet, relay CH operates via wiper CT, locks up via $ch_1, 41$ and switches through the connection to wipers CA, CB at ch_3, ch_4 . Relay IH does not operate at this time since contact 62 is operated and contacts 81 are in their normal position due to relay 8 being released. Dialling to the succeeding switching stage can take place via wipers CA, CB.

When the switch CR reaches the wanted group marked by switch IR a self-stepping circuit is formed for switch IR via interrupter contacts $k_3, ch_2, 61, 92, ch_5, 71, 31$ to earth and subsequently when relay CH operates via contacts 63, $ch_7, 81$ to earth. When the switch IR reaches the contacts selected by CR, relay 8 operates via contacts $ch_{10}, 73, k_9$ and wipers M, N, to stop IR. Relay IH then operates via $k_7, ch_8, 62, 81$ to earth

to transfer the connection at i_3 , i_4 from wipers CA, CB to IA, IB. The common control relays and relay K are released, switch CR homes, and relay IH locks up to the test conductor via i_5 , i_1 .

When the release takes place, relay IH de-energizes and switch IR homes via k_3 , i_2 , and off-normal contacts IN2.

Relay P is a two-step relay which is operated by earth over time-pulse conductor TP to close contact p_2 only. When the first pulse is removed, relay P locks up over both windings via contacts p_2 , 22 and conductor TP is connected over contacts p_1 , ch8, k_7 , to relay IH. If relay CH is not operated before the next pulse on TP, relay IH will operate and lock up, and the control circuit will be released.

What is claimed is:

1. In or for an automatic or semi-automatic telephone system, selecting means comprising a plurality of single-motion switches, groups of outlets from said selecting means, multiple connections for certain of said groups to the later portion of the bank of one of said switches and to the earlier portion of the bank of another of said switches, and connections for the remaining groups connected to the earlier portion of the first-mentioned switch.

2. In or for an automatic or semi-automatic telephone system, selecting means as claimed in claim 1, comprising impulse-responding means, and discriminating means adapted to be set in accordance with the number of impulses received by the impulse-responding means, to select the switch in the early portion of the bank of which the group of outlets corresponding to the number of impulses received is located.

3. In or for an automatic or semi-automatic telephone system, selecting means comprising a plurality of single-motion switches, groups of outlets from said selecting means, multiple connections for certain of said groups to the later portion of the bank of one of said switches and to the earlier portion of the bank of another of said switches, and connections for the remaining groups connected to the earlier portion of the first-mentioned switch, impulse responding means, discriminating means adapted to be set in accordance with the number of impulses received by the impulse-responding means, to select the switch in the early portion of the bank of which the group of outlets corresponding to the number of impulses received is located, and further means adapted to be operated if the required group

is in the second-mentioned switch to move the first-mentioned switch to a corresponding position.

4. In or for an automatic or semi-automatic telephone system, selecting means comprising a single-motion conversation

switch, a single-motion auxiliary switch, groups of lines multiplied in sequence in the banks of the conversation switch, multiple connections for the latter half of said sequence of groups in substantially the first half of the bank of the auxiliary switch, marking contacts at the beginning of the bank of the auxiliary switch for the first half of the groups in the conversation switch, marking contacts in the banks of the conversation switch for the groups in the first half of the auxiliary switch, impulse-responding means, driving magnets for the switches and means for repeating a number of impulses received equal in number to the number of groups in the first half of the conversation switch to the magnet of the auxiliary switch, and any further impulses to the conversation switch.

5. In or for an automatic or semi-automatic telephone system, selecting means comprising a single-motion conversation switch, a single-motion auxiliary switch, groups of lines multiplied in sequence in the banks of the conversation switch, multiple connections for the latter half of said sequence of groups in substantially the first half of the bank of the auxiliary switch, marking contacts at the beginning of the bank of the auxiliary switch for the first half of the groups in the conversation switch, marking contacts in the banks of the conversation switch for the groups in the first half of the auxiliary switch, impulse-responding means, driving magnets for the switches and means for repeating a number of impulses received equal in number to the number of groups in the first half of the conversation switch to the magnet of the auxiliary switch, and any further impulses to the conversation switch, and further means for stepping the switch which is not receiving the impulses towards the required group of contacts during the reception of the impulses.

6. In or for an automatic or semi-automatic telephone system, selecting means comprising a single-motion conversation switch, a single-motion auxiliary or by-path switch, groups of lines multiplied in sequence in the banks of the conversation switch, multiple connections for the latter half of said sequence of groups in substantially the first half of the bank of the auxiliary or by-path switch, marking contacts at the beginning of the bank of the auxiliary or by-path switch for the first half of the groups in the conversation switch, marking contacts in the banks of the conversation switch for the groups in the first half of the auxiliary or by-path switch, impulse-responding means, driving magnets for the switches and means for repeating a number of impulses received equal in number to the number of groups in the first half of the conversation switch to the magnet of the auxiliary or by-path switch, and any further impulses to the conversation switch.

versation switch to the magnet of the auxiliary or by-path switch, and any further impulses to the conversation switch, and means for stepping the conversation switch to a predetermined off-normal position immediately preceding the marking contacts while the auxiliary or by-path switch is receiving impulses.

7. In or for an automatic or semi-automatic telephone system, selecting means comprising a single-motion conversation switch, a single-motion auxiliary or by-path switch, groups of lines multiplied in sequence in the banks of the conversation switch, multiple connections for the latter half of said sequence of groups in substantially the first half of the bank of the auxiliary switch, marking contacts at the beginning of the bank of the auxiliary or by-path switch for the first half of the groups in the conversation switch, marking contacts in the banks of the conversation switch for the groups in the first half of the auxiliary switch, impulse-responding means, driving magnets for the switches and means for repeating a number of impulses received equal in number to the number of groups in the first half of the conversation switch to the magnet of the auxiliary switch, and any further impulses to the conversation switch, means for stepping the marked switch to find a line in the marked group, and means for stepping the conversation switch to the outlet corresponding to a selected outlet in the auxiliary or by-path switch.

8. In or for an automatic or semi-automatic telephone system, selecting means comprising a single motion conversation switch and two single-motion auxiliary switches, groups of lines multiplied in sequence in the banks of one auxiliary switch, multiple connections for the latter half of said sequence of groups in substantially the first half of the bank of the second auxiliary switch, marking contacts at the beginning of the bank of the second auxiliary switch for the first half of the groups in the first auxiliary switch, impulse-responding means, driving magnets for the switches, and means for repeating a number of impulses equal in number to the number of groups in the first half of the bank of the first auxiliary switch to the magnet of the second auxiliary switch, and any further impulses to the first auxiliary switch.

9. In or for an automatic or semi-automatic telephone system, selecting means comprising a single motion converation switch, a single-motion auxiliary switch, and another single-motion auxiliary switch, groups of lines multiplied in sequence in the banks of one auxiliary switch, multiple connections for the latter half of said sequence of groups in substantially the first half of the bank of the second auxiliary switch, marking con-

tacts at the beginning of the bank of the second auxiliary switch for the first half of the groups in the first auxiliary switch, impulse-responding means, driving magnets for the switches, and means for repeating a number of impulses equal in number to the number of groups in the first half of the bank of the first auxiliary switch to the magnet of the second auxiliary switch, and any further impulses to the first auxiliary switch, and further means for stepping the switch which is not receiving the impulses towards the required group of contacts during the reception of the impulses.

10. In or for an automatic or semi-automatic telephone system, selecting means comprising a single motion conversation switch and two single-motion auxiliary switches, groups of lines multiplied in sequence in the banks of one auxiliary switch, multiple connections for the latter half of said sequence of groups in substantially the first half of the bank of the second auxiliary switch, marking contacts at the beginning of the bank of the second auxiliary switch for the first half of the groups in the first auxiliary switch, impulse-responding means, driving magnets for the switches, and means for repeating a number of impulses equal in number to the number of groups in the first half of the bank of the first auxiliary switch to the magnet of the second auxiliary switch, and any further impulses to the first auxiliary switch, and any further impulses to the first auxiliary switch and means for stepping the first auxiliary switch and means for stepping the first auxiliary switch to a predetermined off-normal position immediately preceding the marking contacts while the second auxiliary switch is receiving impulses.

11. In or for an automatic or semi-automatic telephone system, selecting means comprising a single motion conversation switch, and two single-motion auxiliary switches, groups of lines multiplied in sequence in the banks of one auxiliary switch, multiple connections for the latter half of said sequence of groups in substantially the first half of the bank of the second auxiliary switch, marking contacts at the beginning of the bank of the second auxiliary switch for the first half of the groups in the first auxiliary switch, impulse-responding means, driving magnets for the switches, and means for repeating a number of impulses equal in number to the number of groups in the first half of the bank of the first auxiliary switch to the magnet of the second auxiliary switch, and any further impulses to the first auxiliary switch, means for stepping the marked switch to find a line in the marked group, means for stepping the first auxiliary or by-path switch, to the outlet corresponding to a selected outlet in the second auxiliary switch, multiple connections for all said groups in the banks of the conversation switch, and means for stepping said conversation switch to the outlet corresponding

to the outlet to which the first auxiliary or by-path switch is set.

12. In or for an automatic or semi-automatic telephone system, selecting means comprising a single-motion conversation switch in the banks of which groups of outlets are multiplied, an impulse registering and marking switch, an auxiliary switch having two sets of wipers and contact levels, in each of which half the groups of contacts multiplied to the conversation switch are connected, wiper switching means for said auxiliary switch, means whereby said auxiliary switch selects an outlet in a wanted group in accordance with the setting of the register switch, and further means whereby the conversation switch is set to the outlet corresponding to that selected by the auxiliary switch.

13. In or for an automatic or semi-automatic telephone system a switching stage comprising a conversational switch and two auxiliary switches, said switches having groups of outlets connecting in multiple certain of said groups to the latter portion of the bank of one of said switches and to the earlier portion of the bank of another of said switches, characterized in this that means is provided whereby in response to a digit of a predetermined value one of said auxiliary switches is adapted to engage a group of outlets indicated thereby at a position nearer the home position than the position subsequently taken up by the other of said auxiliary switches, the position subsequently taken up by the latter being effective to mark a corresponding position in the conversational switch.

14. In an automatic or semi-automatic telephone system a selecting stage comprising a plurality of single motion switches, impulse responding means and discriminating means adapted to set up a conversational connection immediately upon receipt of certain values of a digit and a temporary connection over a by-path switch for other values of the digit.

15. In or for an automatic or semi-automatic telephone system circuit arrangements as claimed in claim 13 characterized in this that there is at the switching stage an auxiliary control or by path circuit comprising an auxiliary switch adapted to be connected in common with a number of conversational switches.

JOHN HENRY ELVIDGE BAKER.
